MERRITT GALLY, OF ROCHESTER, NEW YORK, ASSIGNOR TO ALLEN P. CARPENTER, OF SAME PLACE.

Letters Patent No. 97,185, dated November 23, 1869.

IMPROVEMENT IN PRINTING-PRESSES.

The Schedule referred to in these Letters Patent and making part of the same.

To all whom it may concern:

Be it known that I, MERRITT GALLY, of Rochester, in the county of Monroe, and State of New York, have invented a new and useful Improvement in Printing-Presses; and I do hereby declare that the following is a full, clear, and exact description of the construction and operation of the same, reference being had to the accompanying drawings, making a part of this specification, in which—

Figure 1 is a side elevation, showing the construction and relative arrangement of the ways and pulleys or guides which give direction to the roller-carriage.

Figure 2 is a longitudinal vertical section, showing the construction of the type-bed, arrangement of distributing-cylinders, and combination of levers used for giving motion to the inking-rollers.

Figure 3 is a view, in perspective, of the method of detachment of the same.

Figure 4 is a detached view of a portion of the draw-bar, together with the cap-cam reversed.

Figure 5 is a horizontal section of the entire press, showing all the parts.

Figure 6 is a side elevation, showing the method of working the ink-fountain and vibrating feed-roller by one and the same movement.

Figure 7 is a perspective view of the set-latch for regulating the impression-adjuster.

Figure 8 is a longitudinal section of the same;

Figure 9 is a perspective of ink-fountain, tank or shell, coated or lined with porcelain;

Figures 10, 11, 12, and 13, are end elevations of the impression-adjuster and throw-off;

Figure 14 is a perspective view of the impression-adjuster, when the two wedges or sleeves are connected by a bar;

Figure 15 is a longitudinal and transverse view of the partitions of the chainbered shell forming the type-bed;

Figure 16 is a view of the gripper or frisket-finger, perforated for the use of guides; and

Figure 17, a view of the elastic cut-off for ink-fountains.

Figure 18 is a cross-section of fig. 17 on an enlarged scale.

This invention consists—

First, in an improved construction of the ways which guide the movement of the inking-rollers, said ways bearing such relation to the ink-distributing cylinders as to insure an easy movement to said rollers, and, at the same time, raise them free from the distributing-cylinders on coming in contact with, or leaving the same, and thus avoid the tearing of rollers so frequent in presses where the former are drawn over the distributing-cylinders.

Second, in the construction and use of cams which

govern the movements of the draw-bars, in connection with the driving-crank.

Third, in a compound lever for giving motion to the inking-rollers, one of the single levers of which always has a positive motion at the time of inking the types, while the other parts may be disconnected, if desired, leaving the inking-rollers upon the distributing-cylinder or cylinders for a longer distribution. When the simple levers forming the compound lever are connected, and act together, said inking-rollers have a positive motion in both directions over the types, never being allowed to run down by their own weight.

Fourth, in a device for disconnecting the single levers of which such compound lever is made up, and rendering one portion of the same, together with the inking-rollers, inoperative, while the remaining lever continues in the positive motion above described.

Fifth, in a catch for preventing the said disconnecting-device from being released at any other time than when the single levers, composing the compound lever, are in proper position for connection.

Sixth, in curved wedges, or sleeves, placed between the pins, trunnions, or journals, which sustain the thrust or draught of the impression of a printing-press, and the bearings of such pins or journals, for adjusting the degree of the impression.

Seventh, in a set-latch, for adjusting the degree of the impression, in connection with the curved wedges or sleeves above referred to.

Eighth, in springs, India-rubber packing, or other elastic material, to take off the positive pressure of the ink-fountain set-screws, so as to prevent the binding of the gauge or cut-off upon the surface of the roller which feeds the ink from the trough or tank.

Ninth, in placing on the lever-projection of the platen-rocker a lug, which, in connection with a flange or stop on the frame-work, holds the platen in position during the impression.

Tenth, in giving the type-bed a backward inclination, when used with a rocking, rolling, vibrating, or oscillating platen, for the purpose of fastening the form to the face of the bed by its own gravity, preventing loose type from working out, and the form "bagging."

In the drawings—

The way $a^1 a^2 a^3 a^4$, which governs the direction of the rollers 1, 2, 3, has a straight part, in line with the face of the types, and a series of curves at that part nearest the ink-distributing cylinder or cylinders.

This series of curves may be varied for different numbers of inking-rollers.

In fig. 1, three inking-rollers are represented, 1, 2, 3, as resting upon the distributing-cylinders 4 5.

The direction of movement of the wheels or guides

7 8 determines the direction of the inking-rollers, as they leave and approach the distributing-cylinders.

Roller 1 simply comes in contact with cylinder 5, and leaves it directly, passing toward cylinder 4. At the same time the rollers 2 and 3 are lifted off from cylinder 4, without being drawn over its surface.

This is done by the movement of the wheels or guides 8 into the curve a^2 .

As roller 1 nears cylinder 4, it also is raised clear of said cylinder, by the passage of wheels or guides 7 into curve a^1 . The wheels or guides 7 and 8 then both pass through curve a^1 into the straight part a^1 .

It will be seen that the passage of the wheels or guides 7 8, through the series of curves a^1 a^2 a^3 , into the straight way a^1 , will give an easy, undulating motion to the rollers, and, at the same time, will prevent the composition of the rollers 1, 2, 3, from being torn, as it is liable to be when said rollers are drawn over the surfaces of the cylinders in the usual manner.

It will also be seen that this arrangement so removes the inking-rollers and distributing-cylinders from the plane of the face of the types as to allow the printing of sheets larger than the face of the platen, or with margins extending beyond the face of the platen, and thus prevents the contact of said sheets with the ink upon said rollers and cylinders.

In fig. 4, the traverse-cam C, in connection with stud or wheel G, governs the movement of draw-bar D, while the crank-pin e is passing through the slot d.

During a part of the sweep of the crank-pin e, it acts in unison with the stud or wheel G, that part of the traverse through which the stud or wheel is passing being concentric with the crank-pin.

The remainder of the traverse being eccentric to the crank-pin, allows the said movement of the latter in the slot d, at the same time holding the draw-bar quiet, so as to impart a time of perfect rest to the plate A.

The traverse may either be a cap, as represented, to be attached to the crank-pin outside of the draw-bar, or it may form part of the crank-wheel inside of the draw-bar.

The combination of levers for giving motion to the inking-rollers is arranged as follows:

H, figs. 1 and 2, is a shaft, to which roller-arms I, fig. 1, are attached, through which, by any means of connection, motion is given to the inking-rollers of a press.

To shaft H, I attach a lever, K, which may be entirely separate from the roller-arms or levers above mentioned, or may form part of one of them.

I also pivot another lever, L, at H², figs. 2 and 3, said lever having a positive vibrating motion, at the time, for moving the inking-rollers over the types, and back again to their position on the distributing-cylinders, such positive motion being imparted by a stud or wheel, O, working in positive traverse-cam C² of the main spur-wheel F, to which traverse-cam, motion is communicated by the driving-shaft E.

I connect the levers L and K by means of a hook-connection, M, pivoted to lever K, at E², and hooked upon a stud or pin, F², attached to lever L.

It will be seen, that when levers L and K are in the position shown in fig. 3, by raising the hook M from the stud E², the lever L will be allowed its positive movement, without motion of the lever K, and, whenever the hook M is hooked upon the stud E², both levers L and K will have a positive motion, acting as a connected compound lever.

As lever L acts through the shaft H, to which the roller-arms or roller-levers are attached, it will be seen that the inking-rollers, when moved in either direction over the types, will have a positive motion, or that said rollers may be retained any length of time upon the inking-cylinders, for distribution, by disconnecting the levers L and K, when in the position represented in fig. 3.

For disconnecting said levers, I use the lever N, with short arms g, said lever being pivoted at f.

It will be seen, in fig. 3, that by working the lever N, the short arm g will raise the hook M, and disconnect the levers L K.

When the hook M is lifted from the stud E², the end of short arm g of lever N moves to a position in front of a projecting portion, i, of lever K, which portion acts as a stop to prevent any movement of lever K during a complete vibration, or a number of vibrations, of lever L.

A drop-hook or latch, P, drops into a connection with a mortise in the end of the short arm g, and prevents the lever N from being worked, except when the levers L and K are in juxtaposition.

The latch P is relieved from the mortise in the end of short arm g by a projection, t², driving against a projection, t¹, of said latch.

It will be seen, that as soon as lever L moves away from lever K, the latch P will fall into position, and prevent the working of lever N at the wrong time, and prevent dropping of hook-connection M.

Upon the pins, trunnions, or journals I, figs. 10, 11, 12, and 13, which sustain the force or draught of the impression of a printing-press, I place curved wedges or sleeves i² or i, the concave face of said wedges or sleeves being concentric with and in contact with said pins, trunnions, or journals I, said wedges or sleeves being placed between said pins, trunnions, or journals and their journal-boxes or bearings.

The convex or outside face of said wedge or sleeve is concentric with and in contact with a part or whole of the concave or inner face of said box or bearings M², the latter made either movable or stationary, in connection with the frame-work, type-bed, or platen, said frame-work, bed, or platen being constructed in any manner, whether the face of said type-bed, or the plate for receiving the sheet, is plane, cylindrical, segmental, or of any other construction; or whether the outside box or bearing M² (either movable or stationary) is used either in connection with impression-bars, connection-rods, draw-bars, or their equivalents, or forms a part of the same.

By turning the sleeve or wedge i i² to different positions about the trunnion, pin, or journal I, the impression may be changed, to any degree, from zero to the strongest power of the press, according as the position of said trunnion, pin, or journal is thus changed with respect to the box or bearing M².

As the surface of pin or journal I and concave face of wedge or sleeve i i², are concentric with each other, and the outside face of said wedge or sleeve and the face of the box or bearing are concentric with each other, said outside and inside faces of said wedge or sleeve being only slightly eccentric with each other, it will be seen, by referring to figs. 11 and 12, that the tendency of the wedge or sleeve to turn under draught or pressure, when set in any position, is very slight. In fig. 11 the wedge i² is represented as a complete crescent, and in fig. 12, it is increased to a sleeve. It will be seen, that when under pressure or draught, one-half of said wedge or sleeve tends to move in one direction, and the other half in an opposite direction, as shown by the direction of the arrows in fig. 11 and fig. 12. As but little difference in the positions of said wedge or sleeve is necessary for any change required in the impression, the variation between the tendencies to turn in either direction will be slight, and more than overcome by the friction of the surfaces under pressure or draught. No device, therefore, is necessary for holding the wedge or sleeve in position while under pressure or draught. Some device, however, is necessary for moving and setting said wedge or sleeve to the degree of impression required, and where two or more of said wedges or sleeves act in unison, some device is required for connecting them together.

In the latter case, I use the connecting-bar T, fig. 14, or an equivalent.

As the friction of the bearing-surfaces in figs. 11 and 12, more than overcomes the tendency of the crescent i^2 to turn under pressure or draught, the position of the crescent cannot be changed when desired, with ease, when any great amount of pressure or draught remains continuous. In such a case, I cut one limb of the crescent away, more or less, thus destroying the equipoise of the two limbs, as shown in fig. 10, or cut one limb of the crescent entirely away, forming the curved wedge i^2 of fig. 13.

In that part of the press A², fig. 7, which contains or supports the pin, trunnion, or journal, with which said wedge or sleeve comes in contact, I place a conical-headed screw, the head of which forms a V-shaped catch, L², for the catch-hook W, in whatever position the screw L² may be turned.

In fig. 1, T represents a projection upon the sleeve or wedge i^2 , or a bar, connecting two or more wedges or sleeves, when more than one are required. Upon the projection or bar T, is a handle, of the following construction:

Through the socket U passes a rod, with a ball or handle, V. Upon said rod is a socket-spring, a, fig. 8, and attached to the end of the rod, opposite handle V, is the catch-hook W. By pressing upon the ball or handle V, the hook W will be released from the catch L², and the wedge or sleeve i^2 , figs. 1 and 14, may be turned, at will, to any position within the scope of its movement. To set the impression to any particular degree desired, it will only be necessary to move the cone L², by turning the screw to which it is attached, out, or further into the supporting-part A², and bringing the hook W and cone L² into connection. This will vary the position of bar or projection T, and thus vary the position of wedge or sleeve i^2 , figs. 1 and 14.

The manner of working the ink-fountain and vibrating feed-roller is represented in fig. 6.

The crooked lever V⁴ works the pawl V³, by contact with a cam, V⁵, on the crank-wheel F.

The ink is fed from the fountain-roller n² on to the vibrating roller V⁶, while rollers n² and V⁶ are in contact, such feeding being effected by the working of the pawl V³ and ratchet n¹; and the same movement of said pawl being continued, forces the vibrating feed-roller V⁶ against the distributing-cylinder 4, said pawl pressing against the vibrating yoke V². This requires but one movement for feeding the ink from the fountain on to the vibrating feed-roller, and also for working the vibrating feed-roller to and from the distributing-cylinder.

I coat or line the tank or shell n, fig. 9, which contains the ink, of an ink-fountain, with porcelain or other substance non-corrosive to ink, to prevent the metallic substance of said tank or shell from corroding or discoloring the ink.

The construction of the bed B is shown in fig. 15, showing an end view and a longitudinal plane section.

The face of the bed is represented by B, the longitudinal braces are represented by l' l'', and the transverse braces by l.

The core-prints or vent-holes, made in casting, are represented by F⁴ and F⁵.

The several braces of the bed converge to a common bearing-line, E, which corresponds with the driving-shaft E of fig. 2.

The bed, constructed as above described, may be made, together with the supporting frame-work, in one piece. In such case, said frame-work will form the end braces l', the bed still remaining a hollow-chambered shell, the core-prints making the openings or vent-holes F⁴ F⁵ through the sides of the supporting frame-work, in those parts which form the end braces.

In applying the spring material to the ink-fountain

gauge, to prevent the binding of the knife or cut-off f³, fig. 17, on the ink-feed roller S⁶, fig. 17, I use the following method, as one of the most convenient in manufacturing and durable for use:

I place a piece or pieces of rubber packing or other elastic material, h, upon the knife or cut-off f³, said material being removed far enough from the edge of said knife as to avoid contact with the ink; I then place upon this elastic material a thin bearing-plate or slips, f⁷, to receive the direct pressure of the set-screws m.

The pressure of said set-screws is conveyed indirectly to the cut-off f³, but prevented from being a positive irresistible pressure by the intermediate elastic material h, so that the flow of ink can be entirely cut off on any part of the length of the roller S⁶, without binding or setting said roller.

The gauge thus constructed is made movable, so that it may be cleaned separately from the roller S⁶.

The holes u u, fig. 16, in the frisket-finger, are made large enough for small feed-guides to be placed under them on the tympan-sheet. These holes have two prominent advantages over notches cut into the side of the finger: first, the finger is much stronger, having material left on all sides of the hole; and second, the entire edge of the finger is left for clamping the sheet, holding it in place more firmly, also preventing tearing or wearing frail sheets, by contact with the corners made by notching the finger.

S, figs. 1 and 5, is the lug, placed on the lever-projection of the platen-support or rocker R, which draws upon the upper face of the flange Y, while projection S² draws upon the under face of said flange, for the purpose of firmly holding the platen in position during the time for taking the impression.

The bed B, figs. 1 and 2, is made to incline backward at any angle between forty-five degrees and the vertical, in order that the type may rest upon the face of said bed, by its own gravity, preventing the loose type from working out of the form, and the latter from "bagging."

I am aware that an inclined bed has been used in connection with a cylinder, by G. P. Gordon, and also in connection with a reciprocating platen inclined parallel to the bed, by P. W. Latcher.

Heretofore the general construction of presses has precluded the use of a bed inclined backward at the same time with a vibrating, oscillating, or rocking platen, on account of the necessarily extended sweep of the platen.

By constructing a platen of the general nature of the one here shown, the sweep is materially shortened, thus allowing the use of such a bed.

Having thus described my invention,

What I claim as new, and desire to secure by Letters Patent, is—

1. In a printing-press, such a construction of the ways in or on which the wheels or guides of the inking-rollers run, as shall raise such inking-rollers free from the distributing-cylinder or cylinders when approaching or leaving the same, substantially as and for the purpose described.

2. The traverse-cam C, whether attached to the crank-pin as a cap or forming part of the crank-wheel, when used in connection with the stud or pulley G, for the purpose set forth.

3. The positively-moving lever L, the lever K, and connection M, combined for the purpose of giving motion to the inking-rollers, arms, or lever s, substantially as described.

4. The lever N g, combined with the connection M, for the purpose of disconnecting the levers L K, substantially as explained.

5. The latch P, combined with the levers L K, for the purpose of holding lever K and hook-connection M in position for reconnection, and preventing the

release of lever N at an improper time, substantially as specified.

6. The wedge or sleeve *i* *i*², pin, trunnion, or journal I, box or bearing M², and adjusting-bar T, combined substantially as and for the purpose set forth.

7. The set-latch L² W, combined with a handle, V, as and for the object explained.

8. In combination with such set-latch, the projection or bar T of the wedge or sleeve *i* *i*², as and for the end specified.

9. The use of rubber packing, or other elastic material, for the purpose of relieving the cut-off of the

ink-fountain from the direct pressure of the set-screws, substantially as set forth.

10. The additional lug S, placed on the lever-projection of support R, in combination with the flange Y, as and for the purpose described.

11. The type-bed B, inclined backward at any angle between the vertical and forty-five degrees, in combination with the vibrating, rocking, or oscillating platen A, constructed substantially as herein set forth.
